UNITED STATES PATENT OFFICE.

JOSEPH A. SAUNDERS, OF QUAKER HILL, INDIANA.

ANIMAL-MUZZLE.

SPECIFICATION forming part of Letters Patent No. 349,408, dated September 21, 1886.

Application filed February 1, 1886. Serial No. 190,477. (No model.)

To all whom it may concern:

Be it known that I, JOSEPH A. SAUNDERS, a citizen of the United States of America, residing at Quaker Hill, in the county of Vermillion and State of Indiana, have invented 5 certain new and useful Improvements in Animal-Muzzles, of which the following is a specification, reference being had therein to the accompanying drawings.

10 My invention relates to improvements in animal-muzzles; and it consists of two bars provided with nose-bulbs pivoted to a muzzle-plate and a spring lock-bar constructed as hereinafter set forth and claimed.

15 In the accompanying drawings, Figure 1 is a front view, and Fig. 2 is a bottom view, showing the pivoted bars closed and locked. Fig. 3 is a front view, and Fig. 4 is a bottom view, showing the pivoted bars unlocked and 20 opened. Fig. 5 is a top view. Fig. 6 is a central vertical section showing the position of the spring and lock-bar when the pivoted bars are closed and locked; and Fig. 7 is the same section showing the position of the 25 spring and lock-bar when the pivoted bars are unlocked.

A designates the muzzle-plate, having on its inner side the concave recess *a*, to form an easy bearing against the nose or lip of the 30 animal.

B B designate bars pivoted to the outside of plate A. The upper portion of these pivoted bars is curved inward and upward, as shown at *h h'*, and terminates with the nose-bulbs *a'*, adapted, in their construction and 35 their location relatively to each other to be inserted and fastened in an animal's nose, and form easy bearings against the cartilage of the nose.

40 C designates a lock-bar constructed the proper size to fit between the lower ends, *b b'*, of the pivoted bars, to lock them in position when the muzzle is placed on an animal's nose. This lock-bar is attached to the lower 45 end of a flat spring, *c*, which is extended upward and attached at the upper end to the plate A. The pivoted bars and the lock-bar spring are partly inclosed by the plate D, secured to the bars *d d' f*, attached to the plate 50 A, which bars are of the requisite thickness to allow space between the plates A D for the pivoted bars to move freely, and these bars *d d'* are placed in position, as shown, to 55 form bearings for the pivoted bars, so as to prevent the nose-bulbs from being pressed

together too tightly against the cartilage of the nose. The under side of the lower portion of the plate D is provided with a recess, *b'*, to allow the requisite play to the lock-bar spring, and the lower edge of the lock-bar is 60 provided with a lip, *c'*, adapting the bar to be readily raised out of its locking position, as seen in the drawings, to allow the pivoted bars to be opened in placing the weaner on and removing it from the nose. The plate A 65 is made the proper length and width to extend downward in front of the animal's mouth, so as to prevent it from sucking, but automatically swings away from the mouth when the head is lowered to eat or drink. The upward curves *h'* of the pivoted bars are designed and adapted to prevent the muzzle from being turned back over the nose. When the animal attempts to thus remove the muzzle from its mouth, the upward curves strike 75 against the front of the nose or head and prevent the upward backward movement of the muzzle-plate.

This muzzle, very simple and inexpensive in construction, is well adapted to prevent a 80 calf from sucking, and also to prevent a cow from sucking herself, and this construction of the device dispenses entirely with the cruel bars commonly used.

I am aware that heretofore calf-weaners 85 have been provided with muzzle-plates and different kinds of attaching devices, and I do not claim such muzzle-plates, broadly; but

What I claim, and desire to secure by Letters Patent, is—

1. The combination of the muzzle-plate A, the pivoted bars B B, arranged in suitable bearings, and provided with the nose-bulbs *a'*, and the lock-bar C, provided with a spring adapted to lock and unlock the pivoted bars, 95 substantially as and for the purposes described.

2. The combination of the muzzle-plate A, the pivoted bars B B, provided with inward and upward curves *h h'* and the nose-bulbs *a'*, 100 and the lock-bar C, provided with a spring adapted to lock and unlock the pivoted bars, substantially as and for the purpose set forth.

In testimony whereof I affix my signature in presence of two witnesses.

JOSEPH A. SAUNDERS.
